CLAIM

The ornamental design for an engine intake manifold, as shown and described.

DESCRIPTION

FIG. 1 is an elevated rear-right perspective view of an engine intake manifold according to the new design;

FIG. 2 is an elevated rear-left perspective view thereof;

FIG. 3 is an elevated front-left perspective view thereof;

FIG. 4 is an elevated front-right perspective view thereof;

FIG. 5 is a rear view thereof;

FIG. 6 is a front view thereof;

FIG. 7 is a right-side view thereof;

FIG. 8 is a left-side view thereof;

FIG. 9 is a top view thereof; and,

FIG. 10 is a bottom view thereof.

The broken lines formed by linear segments of equal length in the figures are provided for environment only and form no part of the claimed design. The broken lines formed by a dash-dot-dash sequence represent an unclaimed boundary.
